UNITED STATES PATENT OFFICE

2,670,944

COAL MINING AND LOADING APPARATUS

Arthur L. Lee, Upper Arlington, Ohio, assignor
to The Jeffrey Manufacturing Company, a corporation of Ohio

Application December 18, 1948, Serial No. 66,080

3 Claims. (Cl. 262—30.)

1

My invention relates to mining apparatus and more particularly to mining apparatus for cutting and loading coal.

An object of my invention is to provide improved coal cutting and loading apparatus.

Another object of my invention is to provide improved mining apparatus for cutting and loading coal wherein there is a coal cutting mining machine and a gathering and loading conveyer disposed along one side of the cutting machine which conveyer loads coal onto a discharge conveyer that follows the cutting machine as it moves bodily about the mine room and which preferably, although not necessarily, travels along and discharges coal into a mine conveyer.

Another object of my invention is to provide improved mining apparatus for cutting and loading coal that includes a coal cutting machine adapted to cut a kerf in a mine room wall and to discharge kerf cuttings from the machine, and a gathering and loading conveyer disposed along one side of the cutting machine for gathering loose and/or semi-compact coal which conveyer may be moved to permit the cutting machine to cut a kerf in the mine room wall and which loads coal onto a discharge conveyer that follows the cutting machine as it moves about the mine room and receives the kerf cuttings discharged therefrom, the discharge conveyer preferably, although not necessarily, traveling along and discharging coal onto a mine conveyer.

Other objects of the invention will appear hereinafter the novel features and combinations being set forth in the appended claims.

In the accompanying drawings,

Fig. 1 is a view in plan of mining apparatus that includes features of my invention, the apparatus including a kerf cutting mining machine of low overall height for cutting a kerf in the solid coal of a mine room wall which machine rests upon and slides over the mine room floor, a loading conveyer also adapted to slide over the mine room floor disposed at one side of the kerf cutting machine for gathering and loading loose and/or semi-compact coal and a discharge conveyer connected to the rear of the kerf cutting machine for discharging kerf cuttings received from the cutting machine and coal received from the gathering and loading conveyer;

Fig. 1a is a sectional view taken on the line 1a—1a of Fig. 2 of the drawings;

Fig. 2 is a side view in elevation of the mining apparatus seen in Fig. 1;

Fig. 3 is a sectional elevational view in plan of a portion of the mining apparatus seen in Fig. 1, the view showing the rear end of the kerf

2

cutting machine, the front end of the discharge conveyer that is connected thereto and a gear box and gear trains through which the gathering and loading conveyer and the discharge conveyer are driven by the kerf cutting machine;

Fig. 3a is a view in elevation, with parts omitted and parts broken away, and showing particularly the structure by which the main frame of the kerf cutting machine and the discharge conveyer are pivotally connected;

Fig. 4 is a view in section, the section being taken substantially on line 4—4 of Fig. 3; and

Fig. 5 is more or less a diagrammatic illustration of mining apparatus performing different mining operations in a mine room, the apparatus embodying other features of my invention and including the mining apparatus seen in Fig. 1 with one end of the discharge conveyer thereof attached to follow and discharge coal onto a mine conveyer as the discharge conveyer follows the kerf cutting machine about the mine room, the apparatus as indicated in dot-dash lines illustrating the gathering and loading conveyer detached from the kerf cutting machine and resting adjacent a side wall of the mine room while the kerf cutting machine is cutting a kerf in the solid coal of the mine room face, and the apparatus as seen in full lines operating to gather loose and/or semi-compact coal shot after the kerf has been cut in the mine room wall;

Referring to Figs. 1, 2 and 5 of the drawings, there is shown mining apparatus which includes a kerf cutting mining machine 10 of the type adapted to rest on and slide over the mine room floor as a unit while cutting a kerf or, in other words, of the well known shortwall type. It is also of a very low overall height to the end that it may be used in very low seam mines. This kerf cutting machine 10 is identical, except for certain modifications herein described, to the mining machine which I have shown and described in my co-pending application, Serial No. 586,979, filed April 6, 1945, now Patent No. 2,660,418, dated November 24, 1953 for a Mining Machine.

With reference to Figs. 1, 2 and 5, and particularly to Fig. 1, the cutting machine 10 may be described briefly as including a main frame 11 that has a forward motor section 12 and a rearward machinery section 13. Attached to the rear end of the machinery section 13 of the main frame 11 is a gummer or cuttings collecting and removing mechanism 14 (see Fig. 4) which discharges kerf cuttings rearwardly from the cutting machine 10.

Extending permanently forwardly from the

motor section 12 of main frame 11 is a kerf cutting mechanism 15 including a long thin cutter bar 16 about which there operates an endless kerf cutter chain 17 provided with removable and reversible cutter bits 18. The rear end of the endless kerf cutter chain 17 operates over a drive sprocket (not shown) positioned adjacent the gummer or cuttings collecting and removing mechanism 14 and discharges coal or kerf cuttings into the cuttings removing mechanism 14 which functions to collect and expel or discharge them from the rear of the cutting machine, as is described in full detail in my Patent No. 2,660,418, above identified.

As is well known, the shortwall type of cutting machine is adapted to be fed as a unit over the mine floor while cutting a kerf, the kerf being cut by first sumping the cutter bar into the solid coal of the mine room face and then feeding the machine bodily laterally across the mine room with the kerf cutting mechanism 15 operating all the while.

To effect feeding of the cutting machine over the mine floor the machine 10 includes a pair of cable or rope feed drums 19 and 20 which are in alignment and one of which is disposed at each side of the machinery section 13 of main frame 11. Drums 19 and 20 are provided with feed ropes or cables 21 and 22, respectively, which are adapted to be reeved about the sheaves of similar right and left hand rear sheave assemblies, one of which is seen at 23 and similar right and left hand front sheave assemblies 25, one of each of which is seen in Figs. 1 and 2. The cutting machine includes a single electric motor which is housed within the motor section 12 of main frame 11 and this motor drives all of the power driven mechanisms of the kerf cutter including the gummer or cuttings removing mechanism 14, the kerf cutter chain 17 and the feed drums 19 and 20 and it tends to drive the feed drums 19 and 20 always in the same direction.

The cutting machine 10 may be fed laterally in reverse directions, and to do this it is provided with means (not shown) for permitting slippage between the driving motor and one or the other of the feed drums to permit it to pay off cable or rope as the other drum winds or reels in its rope. In the lower left hand corner of Fig. 5 of the drawings the machine is illustrated in dot-dash lines with rope 21 reeved about the sheave of the rear sheave assembly 23 and rope 22 reeved about the sheave of the front sheave assembly 25 at the opposite side of the machine and anchored at their ends to mine jacks, stakes or the like to effect lateral feeding of the machine to the left, as viewed from the rear thereof, or downward as viewed from the drawings.

By the mere expedient of reeving rope 21 about the sheave of the other front sheave assembly and reeving the rope 22 about the sheave of the other rear sheave assembly and making the necessary operating adjustments to the machine to cause drum 19 to wind or reel in its rope 21 and drum 20 to slip to pay off its rope 22, the machine may be fed to the right, reversely of that illustrated in said Fig. 5 of the drawings.

By extending both of the feed ropes 21 and 22 forwardly to mine jacks, the machine may be sumped into solid coal. By extending the ropes 21 and 22 rearwardly over auxillary sheaves 26 the machine may be pulled rearwardly away from the mine face.

The mining apparatus of my present inven-

tion includes a discharge conveyer 27 having a main frame that includes a pan shaped bottom member 28 which rests upon and slides over the mine floor. The discharge conveyer 27 is attached at its front end to the rear end of the main frame 11 of the kerf cutting machine 10 to follow or move with it as the kerf cutting machine moves bodily about the mine room floor through a generally U-shaped bracket or tow-bar 29 (see Figs. 1 and 3).

The legs 30 of the U-shaped bracket or tow-bar 29 are connected to the rear end of main frame 11 of the kerf cutting machine 10 to pivot or swing about a horizontal axis through spaced brackets 31 and connecting pins 32 while the rear end or member 33 of bracket or tow-bar 29 is pivotally connected at its center to the pan shaped bottom member 28 of the discharge conveyer 27 through a pivot pin 34.

Pivot pin 34 includes a threaded portion 35 of smaller diameter than the body of the pin that extends through an opening in the end member 33 of bracket 29 and receives a nut 24 that secures the pin 34 to the member 33. That portion of the pivot pin 34 which extends below the member 33 is cylindrical and generally of uniform diameter and is provided with a round convex bottom end which rests upon the bottom of a cup member 36 welded to the pan shaped bottom member 28 of discharge conveyer 27. The cylindrical body portion of the pivot pin 34 is grooved circumferentially and into this groove there extends the rounded ends of two pins 37 that extend through and are secured in diametrically opposite openings in the walls of the cup 36. The width of the circumferential groove in the pivot pin 34 is greater than the diameter of the pins 37 to permit pin 34 to oscillate upon its ball-like bottom end.

It will be seen that the tow-bar 29 and discharge conveyer 27 are pivotally connected for universal swinging movement through the pivot pin 34 and cup 36 and that the tow-bar 29 is connected to the cutting machine 10 for swinging movement about the horizontal axis of pins 32. Because of these connections the cutting machine 10 and discharge conveyer 27 may each rest generally flatly upon and slide over mine floor surfaces which do not lie in a single plane, that is, the planes of the surfaces upon which the cutting machine 10 and the discharge conveyer 27 rest and slide need not be parallel and may be at different elevations. It will also be seen that the cutting machine 10 and discharge conveyer 27 may pivot with respect to each other generally about the axis of pivot pin 34 to permit conveyer 27 to swing generally horizontally about its front end while it follows or is pulled and/or pushed about the mine room by the cutting machine 10.

Discharge conveyer 27 is of low overall height and includes spaced side main frame members 38 supported by the bottom pan 28 between which is carried a plate 39 that cooperates with the side members 38 to form a conveyer trough or way 40 through which there slides the upper or working run of an endless chain and flight conveyer element 41 and below which the return run of the conveyer element 41 slides. Endless chain and flight conveyer element 41 operates over a power driven head or conveyer drive shaft 42 adjacent the front end of conveyer 27 and an idler or tail shaft 43 adjacent the rear end thereof.

Conveyer head shaft 42 carries a sprocket 44 at one side of one of the side members 38 that

70
75

is connected with the drive sprocket of a speed reducer 45 of conventional construction through an endless drive chain 46. Speed reducer 45 is carried upon a bed or base plate 47 that extends laterally from the bottom pan 28 of the discharge conveyer and it is driven from the driving motor of the cutting machine 10 through gearing that is more fully described hereinafter. When speed reducer 45 is driven it drives the endless chain and flight conveyer 40 through chain 46, sprocket 44 and head shaft 42 to cause the working run of the chain 40 to travel rearwardly through the trough or way 40 to convey coal therein rearwardly and discharge it over the tail shaft 43.

The rear or tail shaft end of discharge conveyer 27 is elevated and extends over a mine room or receiving conveyer 48 and this end of discharge conveyer 27 is attached through a rack or truck 49 to the mine conveyer 48 (see Fig. 50). Rack or truck 49 may be of any suitable construction and is carried by the mine conveyer 48 for longitudinal movement therealong and it carries the discharge or tail shaft end of discharge conveyer 27 for pivotal swinging movement through a conventional ball and socket connector 49'. Thus the discharge conveyer 27 may follow the cutting machine 10 while the latter moves about the mine room or across the mine room face; the conveyer 27 all the while discharging the coal onto the mine conveyer 48.

At one side of the kerf cutting machine 10 is an elongated endless chain type gathering and loading conveyer 50 the front end of which is substantially coextensive with the kerf cutting mechanism 16 and which extends substantially from the front of the cutter mechanism 15 along one side of the kerf cutting machine and discharges or loads coal at its open rear end onto the discharge conveyer 27. The gathering and loading conveyer 50 like the kerf cutting machine 10 rests upon and slides over the mine room floor and, like the discharge conveyer 27, it is connected to be moved; that is, pushed and/or pulled over the mine room floor by the cutting machine 10. Gathering and loading conveyer 50 is connected to the side of kerf cutting machine 10 through a pair of brackets 51 and 52. Bracket 51 is formed as a part of the main frame of gathering and loading conveyer 50 and bracket 52 is formed as a part of the motor section 12 of the main frame 11 of cutting machine 10. Brackets 51 and 52 are connected pivotally by a readily and easily removable connector or pivot pin 53.

The main frame of the gathering and loading conveyer 50 includes a track or way that extends from adjacent a drive sprocket 54 at its rear end along one side of the conveyer, around its front end and from the front end back to adjacent the drive sprocket 54. Within this track or way there operates an endless chain gathering and loading element 55 that is driven by the drive sprocket 54 to circulate through the described track or way. Endless chain gathering and loading element 55 carries a plurality of spaced loader elements 56 adapted to gather and move coal that are attached to links of the chain for pivotal movement about horizontal axes whereby the loader elements 56 may be swung from horizontal or gathering and loading positions occupied by them as they travel along the loading side of the conveyor 50 to upright or non-working positions as they travel along the non-loading side thereof, which positions are indicated at 57 and

58, respectively, in Fig. 1. Each of the loader elements 56 includes an extension or portion 59 that extends rearwardly therefrom with respect to the direction of its travel and each of these rearwardly extending portions 59 carries a cutter bit 60 adapted to dig into, cut, break or tear down coal as the gathering and loading conveyer attacks coal to gather and load it. The extension or portion 59 of each of the loader elements 56 also includes a cam or shoe 61 adapted to follow and ride upon a guide bar or strip 62 carried by the main frame of the gathering and loading conveyer 50. Guide bar 62 extends from the front end of the gathering and loading conveyer main frame along its working side to adjacent the drive sprocket 54 at the rear thereof where it cams the shoes 61 of each portion 59 of the loader elements 56 outwardly as the loader elements travel around the drive sprocket 54. The cams or shoes 61 of the loader elements 56 bear against the guide bar 62 on the working side of the gathering and loading conveyer 50 for maintaining the loader elements 56 substantially at right angles to the path of the chain 50 while they are working to gather, convey and discharge coal from the conveyer 50. The main frame of the gathering and loading conveyer 50 also includes an elevating rail 63 that extends forwardly along the non-loading side of conveyer 50 from adjacent the drive sprocket 54 to the front end thereof. Rail 63 adjacent the sprocket 54 cams the traveling loader elements 56 upwardly to their upright or non-working positions as they travel along the non-loading side of conveyer 50 and as the loader elements 56 approach the front end of the conveyer 50 they are cammed laterally by a cam 64 carried on the top of the main frame of conveyer 50 to cause the loader elements 56 to swing outwardly and to be lowered from their upright or non-working positions to gathering and loading positions as they ride upon the rail 63 which is sloped gradually downwardly from adjacent the leading end of the cam 64 to the forward or front portion of the base or ground engaging plate 65 of the conveyer 50.

Conveyer 50 is open along its working side and its rear portion includes an upright side wall 66 that cooperates with the base or ground engaging plate 65 to form a trough or way through which gathered coal is elevated and conveyed rearwardly by the loader elements 56 and loaded upon the discharge conveyer 27 through the open rear end 67 of conveyer 50.

The driving sprocket 54 of conveyer 50 is mounted upon the end of a vertically extending drive shaft of a conventional ring and pinion type speed reducer 68. The main frame of the gathering and loading conveyer 50 is ogee shaped at the rear throughout the length of the upright side wall 66 (see Fig. 2) in order that coal gathered from the mine room floor by the conveyer will be elevated and spilled upon the discharge conveyer 27. The rear end of the main frame of conveyer 50 is carried through the housing of speed reducer 68 which is slidably and pivotally carried by a bracket 69 welded to a side member 38 of the main frame of discharge conveyer 27. Bracket 69 extends horizontally from the side of the discharge conveyer 27 and is slotted longitudinally of the discharge conveyer 27 to receive a pin 70 that extends downwardly therethrough from the housing of the speed reducer 68. Through this mounting the rear end of conveyer 50 is connected to the discharge conveyer

27 for sliding pivotal movement longitudinally of the discharge conveyer.

From the description thus far given it will be seen that the cutting machine 10, the discharge conveyer 27, and the gathering and loading conveyer 50, of my improved mining apparatus, each rest upon and slide over the mine room floor, and that the entire apparatus is slid or moved about the mine room as a unit solely by the cutting machine 10 through its driving motor and ropes 21 and 22. Because the gathering and loading conveyer 50 is attached pivotally to the main frame 11 of cutting machine 10 and its rear end is attached for simultaneous pivotal and sliding movement to the discharge conveyer 27 which in turn is pivoted to the rear end of the kerf cutting machine 10, the entire apparatus, that is, the cutting machine 10, the gathering and loading conveyer 50, and the discharge conveyer 27, is an articulated mechanism wherein each, the cutting machine 10, the gathering and loading conveyer 50 and the discharge conveyer 27 may move, swing or pivot with respect to each of the others to permit the discharge conveyer to swing as it slides over the mine room floor while following the cutting machine 10. When discharge conveyer 27 swings laterally, the gathering and loading conveyer 50 swings about the pivot pin 53 while its rear end follows discharge conveyer 27 by pivoting and sliding along the bracket 69. Coal spilled upon discharge conveyer 27 together with any kerf cuttings discharged by gummer 14 will be conveyed rearwardly by the chain and flight conveyer 41 and spilled or loaded upon the mine conveyer 48 which operates to convey the coal from the mine room.

The kerf cutting machine 10, as fully described in my Patent No. 2,660,418 above identified, includes at its rear end a power take-off shaft which occupies a position in the cutting machine indicated at 71 in Fig. 3. The power take-off shaft is driven from the motor of the cutting machine 10 and the gearing which connects the power take-off shaft with the driving motor includes a clutch that is manually operated through a lever 72 on the cutting machine 10 (see Figs. 1 and 3) whereby the power take-off shaft may be engaged and disengaged from the driving motor. The discharge conveyer 27 and the gathering and loading conveyer 50 are both driven from the power take-off shaft through gear trains seen in Figs. 3 and 4. The gears which make up the gear trains for driving the discharge conveyer 27 and gathering and loading conveyer 50 are housed within a gear box or housing 73 secured directly to the rear end of the cutting machine 10 by bolts 14. Gear box 73 is positioned between the front end of the discharge conveyer 27, the rear end of the cutting machine 10, and above the tow-bar 29.

There extends from the rear or discharge end of the gummer or cuttings removing mechanism 14 and below the gear box or housing 73 an ogee shaped chute or conduit 75 that forms a way which conveys kerf cuttings discharged from the gummer or cuttings removing mechanism 14 onto the front end of the discharge conveyer 27. The rear or discharge end of chute or conduit 75 is supported from the top of the gear box or housing 73 by a pair of straps 76 bolted directly to the top of the housing 73.

There are two gear trains within the housing 73, one for driving the speed reducer 45 and consequently the discharge conveyer 27 and the other

for driving the speed reducer 68 and consequently the gathering and loading conveyer 50. The gear train which drives the speed reducer 45 of discharge conveyer 27 includes a main pinion shaft 77 provided at its front end with an integral disc that carries two spaced projecting pins 78 adapted to extend into wells or sockets in the power take-off shaft of the cutting machine 10 for drivingly connecting the pinion shaft 77 and the power take-off shaft. Shaft 77 extends through the housing 73 and is carried in suitable spaced anti-friction bearings 79 and 80 secured in the housing 73 in a conventional manner as shown in the drawing. Main pinion shaft 77 carries within the housing 73 a main pinion gear 81 that meshes with a reach gear 82 mounted on a shaft 83 through anti-friction bearings 84 and a spacer 85. Endwise movement of shaft 83 is prevented by a shoulder 86 on the shaft and a plate 87 bolted to the rear wall of housing 73. Shaft 83 is retained against rotation in the housing 73 by means of a key 88. Reach gear 82 meshes with and drives a gear 89 that drives a shaft 90 which carries it. Shaft 90 is carried in the housing 73 through anti-friction bearings 91 and 92. Bearings 91 and 92 are mounted in the walls of housing 73 in a manner similar to that by which the bearings 79 and 80 for main power shaft 77 are mounted except that anti-friction bearing 91 at the forward or front end of shaft 90 is received in the bearing cup of a cap or closure member 93 bolted to cover an excess opening in the front wall of housing 73. The rear end of shaft 90 extends through a bearing retaining cap 93' provided with two lubricant, grease or oil seals, one of the friction type and one of the labyrinth type, which surround the hub of a flanged driving member 94 secured by a nut 95 upon and keyed to the tapered rear portion of shaft 90. The flanged driving member 94 carries a universal joint 96 (see Fig. 1) connected to the speed reducer 45 of discharge conveyer 27 through a separable telescoping shaft 97 and a universal joint 98 carried upon the driven or high speed shaft of speed reducer 45.

The gear train through which the gathering and loading conveyer 50 is driven by the motor of the kerf cutting machine 10 includes a reach gear 99 identical to reach gear 82 and mounted in the same manner upon a shaft 100 identical to shaft 83. Reach gear 99 meshes with and drives a gear 101 mounted upon and secured to a cup or body 102 of a slip or overload clutch which drives the shaft 104 upon which it is carried. Overload clutch 103 is generally of conventional construction and it carries in the cup or body member 102 a plurality of friction discs or plates 105 through which the cup or body 102 drives a clutch hub 106 keyed to shaft 104. The friction discs or plates 105 of clutch 103 are pressed together by a friction or pressure ring 107 carried within the cup or body 102 and urged to compress the discs 105 by a plurality of springs 108. Overload clutch 103 is always engaged and it is adapted to slip only should the gathering and loading conveyer 50 become overloaded, jammed or stalled as, for example, by the wedging of coal between its parts.

Shaft 104 is driven from the main pinion shaft 77 through main pinion 81, gear 99, gear 101, and clutch 103, and it is mounted within an enlarged side portion of the gear box or housing 73. The forward end of shaft 104 is carried through an anti-friction bearing 109 secured on the shaft 104 and by a cover 110 in a bearing receiving cup formed in the forward wall of the housing 73. The opposite or rear end of shaft 104 is carried through an anti-friction bearing 111 mounted in

a cap or cover 112 which closes the rear end of the enlarged portion of housing 73. Bearing 111 is carried by the rear end of the shaft 104 and is secured thereon by a nut 113 which clamps its inner race against a thrust washer 114 that abuts a shoulder on shaft 104. A pinion gear 115 is carried for free rotation upon shaft 104 through a bushing 116 and gear 115 and bushing 116 are retained upon shaft 104 against endwise movement by a second thrust washer 117 that abuts a shoulder 118 of shaft 104. Shaft 104 between gear 115 and clutch 103 carries and drives the shiftable driving member 119 of a jaw type clutch 120 which includes ears or lugs 121 on the driving member 119 adapted to engage similar ears or lugs on the side of gear 115. Clutch member 119 receives a shifting yoke 122 by which it is moved along shaft 104 to engage and disengage the clutch 120. Yoke 122 is operated by an arm or yoked member 123 carried for swinging movement by a pivotally mounted rod 124 that is rotated by a manually controlled control lever 125 (see Fig. 4).

Pinion gear 115 meshes with and drives a gear 126 that is keyed upon and drives a shaft 127 situated directly below shaft 104. Shaft 127 is carried at its front end by an anti-friction bearing mounted in the wall in a manner similar to bearing 109 for shaft 104. The rear end of shaft 127 is carried by an anti-friction bearing retained in the cap or cover 112 by a bearing retainer and shaft seal 128 similar to the retainer and seal 93 through which the end of shaft 127 extends. The rear end of shaft 127 receives a flanged driving member 129 (see Fig. 1) like the driving member 94 on shaft 90.

The driving member 129 receives a universal joint 130 that drives a separable telescoping drive shaft 131 similar to drive shaft 97. Drive shaft 131 drives the pinion or high speed shaft of speed reducer 68 for the gathering and loading conveyer 50 through a second universal joint 132 (see Fig. 2).

From the foregoing description of the cutting machine 10 and the gear trains which drive the conveyors 27 and 50 it will be seen that when the operating lever 72 of the cutting machine 10 is moved to engage a clutch thereof to connect the power take-off shaft with the motor of the cutting machine and the motor is energized, the endless chain and flight conveyer 41 of the discharge conveyer 27 will be driven to convey any coal therein rearwardly. It will also be seen that the gathering and loading conveyer 50 cannot be operated unless the discharge conveyer 27 is operated and that it may or may not be driven when the discharge conveyer 27 is operating because the gearing which connects it with the motor of the cutting machine includes the jaw clutch 120.

The gathering and loading conveyer 50 may be disconnected or moved from the kerf cutting machine 10 by removing the pin 53 which connects the main frames of the kerf cutter 10 and the gathering and loading conveyer 50 and by disconnecting the rear end of the conveyer 50 from the discharge conveyer 27 by lifting it to disengage the pin 70 from the slot in bracket 69 and then by moving the conveyer 50 bodily to separate the drive shaft 131.

It may be mentioned here that the only modifications to the kerf cutting machine 10 made in connection with my present invention include the addition of the bracket 52 through which the gathering and loading conveyer 50 is con-

nected to its main frame 11; the addition of a sheave assembly 133 (see Figs. 1 and 2) at a higher elevation than sheave assembly 25 whereby the rope 22 may be caused to extend above the gathering and loading conveyer 50 and over the mine floor at a higher level, the rope 22 being reeved over the sheave of sheave assembly 25 and extending upwardly therefrom and laterally outwardly over the sheave of sheave assembly 133; and the addition of the brackets 31 through which the tow-bar 29 is secured to the rear end of the kerf cutting machine 10.

It may also be mentioned here that the overall height of the entire apparatus (see Fig. 2) is not greater than the overall height of the kerf cutting machine 10 and therefore my improved apparatus for cutting and loading coal is adaptable for use in any coal seam in which the cutting machine alone may be employed.

When the apparatus of my invention is operated to mine coal the first mining operation to be accomplished by it is the cutting of a kerf into solid coal adjacent the mine floor and across the mine room face. When the apparatus is used to cut a kerf the gathering and loading conveyer 50 is removed from the cutting machine 10 and the discharge conveyer 27 and it may be placed as indicated in dot-dash outline in Fig. 5 adjacent the wall of the mine room which is at that side of the kerf cutting machine 10 to which conveyer 50 is attached. The cutting machine 10 is then sumped forwardly into the solid coal of the mine room face, in the manner previously described and well known in the use of short-wall kerf cutting mining machines. When the kerf cutting machine 10 has been sumped into the solid coal of the mine room face the ropes 21 and 22 are connected, as indicated in Fig. 5, to mine jacks or the like positioned adjacent each side wall of the mine room and the kerf cutting machine 10 is fed bodily laterally from the right to the left across the mine room face to a position such as indicated in dot-dash lines in the lower left hand corner of Fig. 5. The cutting machine is then withdrawn from the mine face by connecting the ropes 21 and 22 to other mine jacks to cause its cutter bar 16 to complete the kerf along the dotted line 134. During the sumping and kerf cutting operation above described, the forward end of the discharge conveyer 27 is drawn or pulled about the mine room, the discharge conveyer 27 all the while receiving kerf cuttings discharged from the gummer or cuttings removal mechanism 14 through the chute or trough 75. Because the rear or tail shaft end of discharge conveyer 27 follows along and pivots or swings with respect to the mine room conveyer 48 the discharge conveyer 27 will continuously discharge the kerf cuttings upon the mine conveyer 48 to be conveyed from the mine room.

After the mining machine has been moved away from the mine room face and the kerf cut along line 134 has been completed, the gathering and loading conveyer 50 is connected to the kerf cutting machine 10 and the discharge conveyer 27 and the apparatus, namely, the kerf cutter 10, discharge conveyer 27 and gathering and loading conveyer 50, is moved to the right hand side of the mine room. The undercut portion of the mine room face is then shot in a manner well understood in the mining art, which usually causes the coal above the kerf to fall upon the mine room floor in lumps, as indicated at 135 in Fig. 5, though sometimes the coal remains in

11

a semi-compact and/or standing condition. The coal having been shot the mining apparatus is then employed to gather and load the coal.

In order to gather and load the shot coal, the driving connection between the motor of the kerf cutter and the kerf cutter chain 17 is severed so that the chain 17 does not circulate about the cutter bar 16. The lever 72 is then moved to cause the discharge conveyer 27 to operate and the jaw clutch 120 is engaged to cause the motor of the cutter 10 to drive the gathering and loading conveyer 50. The drive motor of the cutter 10 is now energized and the machine is dumped into the shot coal in a manner similar to that employed when the mining machine is dumped to cut a kerf. Because the conveyer mechanism of the gathering and loading conveyer 50 is capable of digging into and dislodging loose and/or semi-compact coal, the conveyer will gather and move coal rearwardly along the open portion of its working run, which coal will then be conveyed along the upright side wall 66 and discharged or loaded onto the discharge conveyer 27 which, of course, discharges the coal onto the mine conveyer 48. After the gathering and loading conveyer 50 is dumped into the shot coal the rope 22 is reeved over sheave assembly 133 and the kerf cutter is fed from the right to the left side of the mine room in a manner similar to that described and employed when the kerf cutter is cutting a kerf. Having loaded the shot coal, the apparatus is moved away from the mine face and the gathering and loading conveyer 50 is disconnected therefrom and is again placed adjacent the left hand wall of the mine room whereupon the kerf cutting operation may be repeated.

Obviously those skilled in the art may make various changes in the details and arrangements of parts without departing from the spirit and scope of the invention as defined by the claims hereto appended and applicant wishes therefore not to be restricted to the precise construction herein disclosed.

Having thus described and shown an embodiment of the invention, what it is desired to secure by Letters Patent of the United States is:

1. Coal mining apparatus including in combination a coal cutting machine adapted to slide over a mine room floor and including a main frame, means for pulling it about the mine room, cutter bar means having endless kerf cutter chain means operating therearound projecting forwardly from said main frame for cutting a kerf in a mine room wall and means for discharging kerf cuttings from the cutting machine, a discharge conveyer including a main frame adapted to slide over the mine room floor, means pivotally attaching one end of said discharge conveyer to the cutting machine whereby said end of the discharge conveyer receives said kerf cuttings and is moved about the mine room by the cutting machine, a mine conveyer, means mounting the other end of said discharge conveyer to said mine conveyer for pivotal and longitudinal movement therealong, a gathering and loading conveyer including a main frame adapted to gather loose and/or semi-compact coal along one side thereof and to be slid over the mine room floor by and at one side of the cutting machine, said gathering and loading conveyer extending substantially from the front of said cutter bar to behind the rear end of the cutting machine and discharging coal at its rear end onto said discharge conveyer, means detachably pivotally connecting the main frames of said gathering and

12

and loading conveyer and the cutting machine, means detachably pivotally slidably connecting said gathering and loading conveyer adjacent its rear end to said discharge conveyer whereby said gathering and loading conveyer can be removed from said cutting machine and discharge conveyer thereby permitting the cutting machine to operate to cut a kerf in a mine room wall, said cutting machine, gathering and loading conveyer and said discharge conveyer forming an articulated loading apparatus wherein the cutting machine and conveyers are each movable with respect to the others, and gearing connecting said gathering and loading conveyer and said discharge conveyer with the cutting machine to be driven by the latter.

2. Coal mining apparatus including in combination a coal cutting machine adapted to slide over a mine room floor and including a main frame, means for pulling it about the mine room, cutter bar means having endless kerf cutter chain means operating therearound projecting forwardly from said main frame for cutting a kerf in a mine room wall and means for discharging kerf cuttings from the cutting machine, a discharge conveyer including a main frame adapted to slide over the mine room floor, means pivotally attaching one end of said discharge conveyer to the cutting machine whereby said end of the discharge conveyer receives said kerf cuttings and is moved about the mine room by the cutting machine, a mine conveyer, means mounting the other end of said discharge conveyer to said mine conveyer for pivotal and longitudinal movement therealong, a gathering and loading conveyer including a main frame adapted to gather loose and/or semi-compact coal along one side thereof and to be slid over the mine room floor by and at one side of the cutting machine, said gathering and loading conveyer extending substantially from the front of said cutter bar to behind the rear end of the cutting machine and discharging coal at its rear end onto said discharge conveyer, means detachably pivotally connecting the main frames of said gathering and loading conveyer and the cutting machine, and means detachably pivotally slidably connecting said gathering and loading conveyer adjacent its rear end to said discharge conveyer whereby said gathering and loading conveyer can be removed from said cutting machine and discharge conveyer thereby permitting the cutting machine to operate to cut a kerf in a mine room wall, said cutting machine, gathering and loading conveyer and said discharge conveyer forming an articulated loading apparatus wherein the cutting machine and conveyers are each movable with respect to the others.

3. Coal mining apparatus including a main frame, a motor on said main frame, an endless chain and flight coal gathering conveyor extending forwardly and rearwardly of said main frame and operative to gather coal in front of said main frame and discharge it rearwardly thereof, a discharge conveyor positioned to receive coal from said gathering conveyor, a receiving conveyor positioned to receive coal from said discharge conveyor, means pivotally and slidably interconnecting said discharge and receiving conveyors whereby said discharge conveyor may move rectilinearly and laterally relative to said receiving conveyor while continuing to discharge therewith, means connecting said motor to drive both said gathering conveyor and said discharge conveyor, means pivotally con-

13

necting said main frame to said gathering conveyer, means pivotally connecting said main frame to said discharge conveyer, and means pivotally connecting said gathering conveyer and said discharge conveyer, one of said last named pivot means also being rectilinearly slideable whereby said pivotally connected main frame, gathering conveyer and discharge conveyer form an articulated unit.
